UNITED STATES PATENT OFFICE.

LLOYD HUDSON SMITH, OF WACO, TEXAS, ASSIGNOR TO TEXAS STEEL HIGHWAY
MARKER ASSOCIATION, OF WACO, TEXAS.

ROAD MARKER.

1,426,420.

Specification of Letters Patent. Patented Aug. 22, 1922.

Application filed April 21, 1922. Serial No. 555,929.

To all whom it may concern:

Be it known that I, LLOYD HUDSON SMITH, a citizen of the United States, residing at Waco, in the county of McLennan and State of Texas, have invented a new and useful Road Marker, of which the following is a specification.

This invention aims to provide a simple device whereby roads may be marked throughout a state, proper information being given as to bends, cross roads, bridges, and the like, which are in advance, the device being so constructed that it may be manufactured cheaply and without the expenditure of much labor and be well adapted to withstand hard use.

It is within the province of the disclosure to improve generally and to enhance the utility of devices of that type to which the invention appertains.

I do not bind myself to the specific details shown, since a mechanic, working within the scope of what is claimed, may make changes without altering the device in essential points, departing from the spirit, or avoiding the charge of infringement.

Figure 1 shows in elevation, a device constructed in accordance with the invention; Figure 2 is a longitudinal section; Figure 3 is a cross section taken approximately on the line 3—3 of Figure 2; and Figure 4 is a diagrammatic elevation illustrating the way in which the material is cut to form the standard.

In carrying out the invention, there is provided a standard 1, which may be in the form of a piece of pipe if desired, the lower end of the standard ordinarily being mounted in an anchor 2, the anchor being seated in the ground in such a position that the device may be readily visible to a person traveling on the highway. The upper end of the standard 1 is cut away as shown at 3 to form a reduced arm 4 at the upper end of the standard, and to form a transverse shoulder 5 at the lower end of the arm. A vertical seat or notch 6 is cut in the shoulder 5, in alignment with the inner edge of the arm 4. The numeral 7 marks a main plate, which may be of rectangular outline or any other form. The main plate 7 abuts against the arm 4, the lower edge of the plate fitting in the seat 6. Securing elements 8, assembled with the standard 1

and with the arm 4 thereof, hold the plate 55 7 in place. The plate 7 carries a marker 9 of any desired sort, giving information concerning that portion of the road which lies ahead. The mark may be of any conventional or known form, to indicate turns, 60 cross roads, bridges, bad spots, railroad crossings, schools, places of public entertainment, and the like. The plate 7 may be inscribed with a legend 10 which may be the name of the trail or road, advertising material, or anything else. Auxiliary plates 11 are held by securing elements 12 on the standard 1. One of these plates 11 may be inscribed, as indicated at 14, with information concerning the distance to a 70 nearby town or the like. The other plate 11 may be marked with an abbreviation 15 designating the name of the trail.

The device may be colored in any desired way, and in any preferred combination 75 of hues to conform to standard regulations relative to the trail or road or for any other purpose.

Owing to the fact that the main plate 7 is mounted on the standard 1 in the particular way described, practically the entire surface of the plate is available for inscriptions of any kind, and, at the same time, the plate is held securely on the standard 1.

As shown in Figure 4, the pipe or other member 16 out of which the standard 1 is formed, may be cut longitudinally as at 17, and then cut transversely in opposite directions as at 18 in spaced relation to the ends of the longitudinal cut 17. The result is the formation of the arm 4, the shoulder 5 and the notch 6. It is to be observed that no material is wasted, and that one series of cuts will form the upper 95 ends of two standards.

What is claimed is:—

1. In a device of the class described, a standard cut away at its upper end to form a reduced arm and to form a transverse 100 shoulder at the lower end of the arm, the shoulder having a seat; a plate abutting against the arm and received in the seat; and means for securing the plate to the standard.

2. A method of making a standard in a device of the class described, the method consisting in providing a member with a

longitudinal cut, and then providing the said member with transverse cuts, extended inwardly in opposite directions and communicating with the longitudinal cut, the 5 transverse cuts being spaced from the ends of the longitudinal cut.

In testimony that I claim the foregoing

as my own, I have hereto affixed my signature in the presence of two witnesses.

LLOYD HUDSON SMITH.
